UNITED STATES PATENT OFFICE.

JOHN THOMSON, OF NEW YORK, N. Y.

UNIVERSAL ELECTRIC ZINC-FURNACE WITH INTEGRAL CONDENSER.

1,086,418.

Specification of Letters Patent.

Patented Feb. 10, 1914.

Application filed May 8, 1913. Serial No. 766,248.

To all whom it may concern:

Be it known that I, JOHN THOMSON, a citizen of the United States, and a resident of the borough of Manhattan of the city of New York, State of New York, have invented certain new and useful Improvements in Universal Electric Zinc-Furnaces with Integral Condenser, of which the following is a specification, reference being made to the accompanying drawing, forming a part hereof.

The invention relates to the metallurgy of zinc, having for its object the production of zinc fume and its subsequent condensation to liquid metal.

A description of the particular means for attaining the desired results and such an elucidation of the general principles applicable thereto as will adequately disclose the invention will be concurrently pointed out in connection with the description of the accompanying drawings which are representative embodiments of the invention.

Figure 1 is a transverse center section, viewed as indicated by arrows A; Fig. 2 is a partial side elevation; Fig. 3 is a vertical longitudinal section, viewed as denoted by either of the arrows B or B¹ down to the horizontal plane B² and is thence a central section taken as on the plane denoted by the lines C, viewed in either direction, as is indicated by the arrows in Fig. 1; Fig. 4 is a half top plan view on the left hand of center line A, while its right hand portion is a horizontal section along the plane D; and Fig. 5 is a horizontal section, the left hand half of which is along the plane E and the other or right hand half being along the plane F.

This furnace is particularly intended for the reduction of igneous oxid of zinc combined with carbon, when the inert residual of the reaction is of small amount and of an ashy or sintered character, and for any sulfid or oxidized zinc or lead-zinc ores having a considerable content of gangue of such character as is capable of being fluidized.

To avoid explanatory statements which would in fact be in the nature of repetitions, it is stated that this application is more or less correlated with several pending applications filed by the present applicant on January 2nd, 1913; and application bearing Serial No. 739,795 which was filed on said date, is particularly cited. This application is also related to my application bearing

Serial Nos. 760,915 and 760,916, filed April 14th, 1913.

The decomposition of the charge is effected by heat derived by direct conduction or radiation or by both, preferably from electrically incited compound porous bed-resistors, such as are ordinarily formed from pieces of broken carbon interpolated between terminals.

The resistors, as H, are laid parallel to each other, separated by a space I in which several transverse thrust-plates x are disposed. These thrust-plates are preferably of a material which is a non-conductor of electricity. When the resistors are operated in series, as is here shown, one pair of resistor-ends is in contact with carbon terminals 6, 7, while the opposite ends contact with the connector 8, which is situated within the furnace walls. This connector 8 electrically connects the resistors, preferably in series, and may, like the terminals, be formed of a series of carbon blocks, stacked one upon another, as denoted in Fig. 3.

Beneath each resistor is a sump 9, 9^a, across which a series of spaced bars or rods, as 12, are laid and upon which the resistor carbon is supported. These rods constitute a hearth and any desired form of spacing or perforations may be utilized.

Between the longitudinal furnace walls 13, 13^a, and the outer vertical faces of the resistors are open chambers or gaps J, which by means of transverse slabs, as 14, preferably set into the furnace walls, as at 15, sub-divide the gaps into pockets, as 16. The tops of the resistors as also the intervening space I are covered by bricks or tiles, as 17. The charge material K is placed in the said pockets and should also more or less fill the overhead reserve recess L. Obviously, the reaction must take place along or in front of the outer vertical faces of the resistors, the volatilized products thereof passing right and left in horizontal planes from the reaction zones, as c, Fig. 1, through the instices of the carbon resistor and into the central space I. The action and reaction of the heat emitted from the inner vertical faces of the resistors is direct, substantially equal and opposite, as indicated by the arrows d; thus there is comparatively little loss of heat energy from the resistors. The fume and gas after leaving the resistors deflect and flow downwardly, as arrow e,

through a slot or throat 18, or a series of ports, into an underlying longitudinal space or expanding chamber M. In other words, essentially all of the heat carried to or into the said chamber will only be that necessarily stored in the flowing volatile matter whose temperature will be equal, or approximately so, to that of the resistors.

If the material under reaction is of a character to produce a modicum of ashy or sintered residue, such as usually results when igneous oxid of zinc (ZnO) and carbon in the form of coke (C) are brought together or commingled, as for instance, igneous oxid of zinc and coke, both of commercial purity, such ashy or sintered residue may be intermittently withdrawn from the bottoms of the pockets through the openings or ports N formed in the side walls of the furnace, or it may thus be partially or wholly poked forward through the grate-bar spaces, whereby it may fall into the sumps. Contrariwise, if the charge material is combined with gangue capable of being dissolved to a liquid slag, this will run forward along the slopes S and thence through the aforesaid grate-bar spaces down into the sumps, as indicated by the arrows i. Such may also be the case if lead is an element of the charge and is liberated as liquid metal. In certain cases slags from zinkiferous ores, or concentrates thereof, cannot be readily reduced to such a degree of fluidization as will run freely. Consequently small tap-holes are liable to "freeze" even after an opening has been effected. The opening of the small tap-holes is often quite difficult and this objection has been obviated by leaving all or a considerable portion of the outlet end or ends of the sump open and forming an outer recessed portion against whose abutment, as 19, Figs. 3 and 4, in initial closure is effected by means of a thin refractory plate, as 20, upon whose inner face a layer of suitable fire-clay paste, as 21, has been applied. Once the sump is emptied, such a plate may be easily and quickly thrust into contact with the abutment at which the fluid-seal is made. The plate is then held securely to its position, and any serious emission of heat is also thereby avoided by inserting a large free block, as 22, supported and additionally sealed as by a packing of granular carbon or sand 23. When the sump is to be emptied the aforesaid free block is removed, the thin inner plate or seal is smashed inwardly and the slag is thus almost instantly liberated free to flow out in large volume, if in a fluid state or to be scraped out if in a pasty condition. While a new plate requires to be furnished after each tapping, the cost thereof is negligible and of little consequence when compared to the advantages derived from the use of such a construction. In this context it may be best to here point out that the connector S which

would ordinarily be artificial graphite of high heat conductivity, is preferably supported across the sumps by a relatively thin refractory, as 24, Fig. 3, set immediately above and contiguous to the tap openings. Yet the said refractory 24 may be dispensed with, but there would then be some risk of burning due to the entrance of a small amount of air when the ends of the sumps are open. To prevent or minimize this burning which is liable to take place, the slag or other liquid matter is maintained hot close up to the sealing plate. The connector is preferably set upon a layer of unbound granular material, such as carbon or carborundum, and is also backed with a layer, as 25, of the same character. In this wise, by removing the top layers of bricks, the backing may be packed down or be more or less removed at one end or the other of the connector, whereby to equalize the intimacy of contact, thrust or pressure upon the resistors and to balance the thermal effects therein by increasing or decreasing their relative electrical resistances.

The horizontal zone of the furnace beneath the plane indicated by the arrows B² or F, constitutes the condenser, and it is preferably comprised in a series of lateral chambers P formed by the septums 26 which also serve as supports for the superimposed structure. These chambers may be filled with broken filter carbon, as 27, or with spaced or laminated diffusing plates, as 28, or with any arrangement of staggered rods or plates, such as 28^a, 29, Fig. 5, or with any combination thereof, as may be desired. The outer ends of these chambers may be left open, or they may be inclosed, as 30, Fig. 1, having a slot, or tube as 31, for the escape of residual gases, or outer sheet metal casings, as 31^a, may be employed, open at the top, as 32, from whence CO passes to atmosphere. The bottoms of the chambers P are preferably formed of tamped material 33, impervious to molten metal, sloped downwardly each way from the longitudinal center of the furnace and connecting with suitable spouts, as 34, 34^a, for conducting off liquid zinc.

It will now be perceived that the hot fume and gas will be ejected from the throat 18 at relatively high velocity, expanding and filling the chamber M, thence deflecting and flowing right and left through the condensing chambers, as indicated by arrows m, m¹. During this transit, if the chambers are filled with broken carbon or the spaces between the plates or rods are vertical, the lighter gas, as denoted by arrow n, Fig. 1, will rise, the denser fume, as denoted by arrow r, will fall and the condensed zinc will precipitate upon the sloped bottom or sole and thence flow down to and out at the spouts.

The diminution in temperature between the fume and gas in the space between the resistors and that in the expanding chamber

will, at a normal maximum rate of reaction, be but trifling, and as the slag-sumps are above and contiguous thereto the heat loss from the sumps, by conduction downwardly, is thus so nearly completely compensated as to be merely nominal; therefore the drain of energy from the lower portions of the resistors becomes negligible.

In constructing the furnace it is preferable that at least one or two courses of the bricks beneath the tamped bottoms of the condensing chambers, as 35, and at the extreme ends, as 36, Figs. 1, 2 and 3, should be of the best quality of non-heat-conductive material. Now, assuming an adequate realization of the several foregoing features, it necessarily follows that essentially all of the heat units of the fume and gas which is conveyed to the expanding chamber can only be dissipated in horizontal directions, and that as the drop in temperature between the longitudinal center of the furnace and the outer ends of the condensing chambers may be of any difference desired, or as between that of the inner hot gases and the outside atmosphere, it will be apparent that the ideal conditions essential for complete and effective condensation of zinc fume to liquid metal are realized. Or to otherwise express it, the temperature drop will progress in uniform increments from the entrance to the exits of the condensing chambers, the ultimate discharge of temperature and calories being practically solely from the muzzles thereof. Consequently, as the filter carbon or the plates, or the rods within the condensing chambers, as the case may be, cannot transmit heat in sensible amount at right angles to the direction of the flowing fume and gas, but solely in the direction of their flow, it simply becomes necessary to control the rapidity of heat radiation from the outer ends of said chambers, that is, relative to the volume of hot fume and gas delivered into the expanding chamber. To realize this condition, as has already been pointed out, the ends of the condensing chambers may be left open to atmosphere, or they may be inclosed by heads more or less thick and of material more or less heat-conductive. Moreover, if the evolution of fume is at so low a rate as not to require the entire condensing capacity of all the chambers, then one or several of them may be completely sealed, that is, cut out; or if the rate of evolution is beyond the capacity of all the condensing chambers, even when delivering their residual gases direct to atmosphere, the metal shields 31 may be employed whereby any impinging fume, as arrow *v*, would be chilled and regained as "blue powder".

The unique accessibility of the principal coördinating elements of this design is a feature which in an industrial sense is second

only to the functions performed. Thus, by removing the tiles 17 the resistors are exposed for examination or partial renewal or entire replacement, and the space between the resistors, the throat and the expansion chamber are also entirely free for inspection and the dislodgment of oxidized or carbonaceous matter, should such have accumulated. Furthermore, with respect to the condensing system, the same conditions ⁷⁰ ₇₅ ₈₀ ₈₅ ₉₀ ₉₅ ₁₀₀ ₁₀₅ ₁₁₀ ₁₁₅ ₁₂₀ ₁₂₅ ₁₃₀ ₁₃₅ ₁₄₀ ₁₄₅ ₁₅₀ ₁₅₅ ₁₆₀ ₁₆₅ ₁₇₀ ₁₇₅ ₁₈₀ ₁₈₅ ₁₉₀ ₁₉₅ ₂₀₀ ₂₀₅ ₂₁₀ ₂₁₅ ₂₂₀ ₂₂₅ ₂₃₀ their capacity to conduct and dissipate heat. The longitudinal expansion chamber M may itself be more or less filled with carbon or plates, but the restriction of the filtering or diffusing material to the condensing chamber spaces appears to be the more advantageous. Again, instead of having a distinct spout from each chamber, a zinc receptacle may be formed in the bottom to pass through the furnace longitudinally, thereby collecting the liquid metal from all, or from each right and left hand series of the chambers and delivering it at a single spout.

The mention of the foregoing modifications is regarded as a sufficient attestation that various others may be made by those skilled in the art without departing from the fundamental features of this invention.

What I claim is:

- 20 1. In an electric zinc furnace, porous carbon resistors, parallel charging gaps or pockets, ports in the furnace side walls, gratings upon which the resistors are sustained and sumps beneath the gratings, said ports being arranged so that an ashy or sintered residue is removable therethrough, and the gratings being arranged so that fluidized metal and slag flow into the sumps.
- 25 2. An electric zinc furnace having parallel carbon resistors electrically connected in series within the furnace by a carbon connector having a space at the rear thereof filled with free or unbound granulated refractory matter.
- 30 3. In an electric zinc furnace having parallel carbon resistors and underlying sumps, said resistors being connected within the furnace so as to be electrified in series by a carbon connector which is arranged to span one or both of the underlying sump or sumps at or contiguous to the sump tap-openings.
- 35 4. An electric furnace having carbon resistors for operating in series, an electrical connector therefor and sumps below the resistors, the connector being located above and spanning the sumps.
- 40 5. In an electric furnace, a longitudinally extending sump having an open tap-end closable by a separate refractory plate thrust against an abutment by an outer block.
- 45 6. In an electric furnace, a sump whose tapping opening is closed by an upright refractory plate which is broken when the contents of the sump are to be withdrawn.
- 50 7. An electric zinc furnace having adjacent to the lower portion of the carbon resistor a sump for receiving fluidized metal and slag, said sump having its tap opening closed by a separate plate which is broken when the sump contents are to be withdrawn.
- 55 8. An electric zinc furnace comprising

charging gaps or pockets, porous carbon resistors or a resistor, from whence the volatilized products of the reaction are derived, and a plurality of underlying condensing chambers, the furnace being provided with a gap or throat through which the fume and gases pass from the resistors to the chambers.

9. In an electric zinc furnace, parallel porous carbon resistors which have a free space between them, charge-receiving pockets arranged along the outside vertical faces of the resistors, and a condensing system in the base of the furnace, the furnace comprising a portion having a slot, throat, port or ports through which the fumes flow in passing from the space between the resistors to the interior of the condensing chambers.

10. In an electric zinc furnace, a plurality of transversely disposed condensing chambers located in the base of the furnace, and an overhead portion provided with a longitudinal slot, throat or series of ports which connect the chambers to a superimposed source of supply of fume and gas.

11. In an electric zinc furnace, a sump upon which a carbon resistor is sustained and beneath and contiguous to which is the hot zone of a condensing system.

12. An electric zinc furnace having spaced parallel resistors and a condensing system comprising a plurality of chambers which receive from the space between the resistors the hot volatilized products of the reaction at their inner ends and which discharge any residual gases at their outer ends to atmosphere.

13. In an electric zinc furnace, a condensing system comprising a plurality of horizontal chambers having therein filter members, said chambers being so arranged and disposed that the filter members may be removed or replaced from along the outer side walls of the furnace.

14. In an electric zinc furnace, a condensing system comprising a plurality of chambers more or less filled with filter members between which the fume and gases flow laterally but are free to separate vertically according to their respective densities.

15. In an electric zinc furnace, two series of transversely disposed condensing chambers having a central longitudinal expanding chamber into which the volatilized products of the reaction are delivered vertically and from whence all of the said condensing chambers are supplied horizontally.

This specification signed and witnessed this 7th day of May, 1913.

JOHN THOMSON.
